UNITED STATES PATENT OFFICE.

CHARLES H. WINNE, OF TROY, NEW YORK, ASSIGNOR OF ONE-HALF TO FREDERICK C. CLAESSENS, OF TROY, NEW YORK.

MARKING DEVICE.

1,369,512.

Specification of Letters Patent. Patented Feb. 22, 1921.

Application filed September 24, 1920. Serial No. 412,447.

To all whom it may concern:

Be it known that I, CHARLES H. WINNE, a citizen of the United States, residing at Troy, in the county of Rensselaer and State 5 of New York, have invented certain new and useful Improvements in Marking Devices, of which the following is a specification.

This invention relates to marking devices, and the primary object of the invention is 10 to provide an improved changeable stamp particularly adapted for marking price codes in articles of manufacture in retail houses and the like, the stamp being so constructed that the type can be quickly and easily 15 changed and held in operative position against accidental displacement.

Another object of the invention is to provide a marking stamp having a novel type of handle arranged for receiving and holding the surplus marking characters and adapted for actuating the clamping member for holding the marking characters which are to be used in the stamping operation.

A still further object of the invention is 25 to provide an improved marking device of the above character which is durable and efficient in use, one that is simple and easy to manufacture, and one which can be placed upon the market at a reasonable cost.

With these and other objects in view, the invention consists in the novel construction, arrangement and formation of parts as will be hereinafter more specifically described, claimed and illustrated in the accompanying 35 drawings, forming a part of this specification, in which drawings:

Figure 1 is a perspective view of the improved marking stamp showing certain of the characters being held in operative stamping position against accidental displacement.

Fig. 2 is a vertical central section through the stamp showing certain of the marking characters being held in operative position.

Fig. 3 is a fragmentary vertical transverse 45 section through the stamp showing certain of the marking characters being held in marking position.

Fig. 4 is a horizontal section through the same, and

Fig. 5 is a plan view of the handle for the improved stamp.

Referring to the drawings in detail, wherein similar reference characters designate corresponding parts throughout the several 55 views, the letter A generally indicates the

improved stamp which includes the clamp B for the characters C and the handle D.

The clamp B for the characters C includes a bed plate 10 and the base plate 11. These plates 10 and 11 are held in spaced relation 60 to each other by means of spaced posts or rods 12. These rods 12 are arranged adjacent to the opposite ends of the plates 10 and 11 and at the longitudinal medial line thereof. These posts or rods 12 have their terminals upset as clearly shown in Fig. 2 of the drawings. A clamping plate 13 is slidably mounted between the plates 10 and 11 and has its side edges notched as at 14 for receiving the posts or rods 12, which 65 form guide members for the same. The bed plate 10 is of substantially rectangular configuration and is provided with a longitudinally extending slot 15, through which the marking characters C are adapted to extend. 70 One longitudinal edge of the bed plate 10 is provided with a right angularly disposed flange 16 which forms a guide for alining the marking characters C in correct relation to each other. The central portion of 75 the clamping plate 13 has swivelly mounted therein the depending screw 17, which is mounted in a centrally disposed threaded opening 18. The lower surface of the clamping plate 13 is adapted to engage the upper 80 surface of the marking character C which 85 will be now described.

Each of the marking characters C includes a base 19, which extends substantially the entire width of the bed plate 10 and the depending marking portions 20 which are adapted to extend through the slot 15 formed in the bed plate. The upper end of the screw 17 is formed integrally with or rigidly connected to the handle D which will be now 90 described. The handle D is preferably of hollow configuration and is of a substantially inverted truncated conical shape and the hollow handle is adapted to receive the surplus marking characters designated by 95 the numeral 21. The upper end of the hollow handle D is provided with a substantially semi-circular rigid top plate or cover 100 22. This rigid cover 22 extends over substantially one half of the upper end of the hollow handle D and forms a bearing 23 for the rotatable pin 24, which carries the movable cover plate 25, which is also of a substantially semi-circular configuration. The 105 movable cover plate 25 is adapted to be 110

5 moved over the rigid cover plate 22 so as to permit access to be had to the interior of the hollow handle. The pin 24 has secured thereto a thumb piece 26 whereby the operation of the movable cover plate 25 is considerably facilitated.

In operation of the improved stamp the characters which are to be used, are removed from the hollow handle D and the hollow handle D is rotated in such a direction as to feed the screw 17 upwardly which will move the plate 13 away from the bed plate 10. This will permit of the easy removal and placing of the characters in the slot 15 and the bases 19 thereof will extend beyond the longitudinal side walls of the slot. The provision of the guide flange 16 permits the perfect alignment of the characters in relation to each other. The hollow handle D 20 is then turned in a reverse direction which will feed the plate 13 into tight engagement with the characters C. The displacement of the characters C while the stamp is in use is absolutely prevented, owing to the firm 25 engagement of the plate 13 with the characters and the engagement of the bases 19 of the characters with the bed plate 10. The stamp is then used in the ordinary manner and owing to the exceptionally simple and 30 durable construction thereof, the life of the stamp will be considerably enhanced.

Changes in details may be made without departing from the spirit or scope of this invention; but,

35 I claim:

1. A marking device comprising a pair of spaced superposed plates, a pair of guide posts carried by and arranged between the plates, one of the plates having a slot therein, stamping characters adapted to be fitted in said slot, a movable clamping plate arranged between the first mentioned plates, and means for moving the clamping plate toward and away from the stamping characters.

2. A marking device comprising a bed plate, a base plate arranged in superposed relation to the bed plate, and a pair of guide posts arranged between the plates, a sliding clamping plate arranged between the first mentioned plates and slidably carried by said guide posts, the bed plate having a longitudinally extending slot therein, marking characters arranged to fit in said slot, 50 the marking characters having bases arranged to engage the upper surface of the

bed plate on opposite sides of the slot formed therein, a handle, and means actuated by the handle for moving the clamping plate toward and away from the stamping characters.

3. A marking device comprising a pair of superposed plates, guide posts carried by and arranged between the plates, a clamping plate arranged between the first mentioned plates and slidably carried by said posts, one of said plates having a longitudinally extending slot formed therein, marking characters including bases, and marking faces, the faces being adapted to extend 70 through the slots and the bases arranged to engage the plate on each side of the slot, a hollow handle, a screw carried by the handle, and means swivelly connecting the screw to said clamping plate. 75

4. A marking device comprising a rectangular shaped bed plate, a base plate arranged in superposed relation to said bed plate, a pair of guide posts carried by and securing the plates together, a clamping 80 plate arranged between the bed and base plates and slidably carried by the guide posts, the bed plate having a slot therein, marking characters arranged to fit in said slot, a right angularly upstanding flange 85 formed on one longitudinal edge of the bed plate for engaging said marking characters, the base plate having a threaded opening formed therein, a screw threaded in said opening, means swivelly connecting the 90 lower end of the screw with the clamping plate, and a handle rigidly connected to said screw.

5. A marking device comprising a pair of superposed plates, one of the plates having a slot therein, marking characters arranged to fit in said slot, a slideable clamping plate arranged between the first mentioned plates, a handle, and means connecting the handle with said clamping plate for moving 100 the same toward and away from said marking characters.

6. A marking device comprising a pair of plates, one of the plates having a slot therein, stamping characters arranged to fit 105 in said slot, and means arranged between the first mentioned plates for movement toward and away from the stamping characters for holding the stamping characters in position against accidental displacement.

CHARLES H. WINNE.
